Inventor:

Samuel Walker

UNITED STATES PATENT OFFICE.

SAMUEL WALKER, OF KINGSTON, GEORGIA.

IMPROVEMENT IN PLOWS.

Specification forming part of Letters Patent No. 26,633, dated December 27, 1859.

To all whom it may concern:

Be it known that I, SAMUEL WALKER, of Kingston, in the county of Cass and State of Georgia, have invented a new and Improved Plow; and I do hereby declare that the following is a full, clear, and exact description of the same, reference being had to the annexed drawings, making a part of this specification, in which—

Figure 1 is a side elevation of my invention. Fig. 2 is a plan or top view of the same.

Similar letters of reference indicate corresponding parts in the two figures.

The invention is more especially designed for what are known as "shovel-plows," used in the cultivation of southern crops, but it may be applied with advantage to other small plows used as cultivators in tilling growing crops.

To enable those skilled in the art to fully understand and construct my invention, I will proceed to describe it.

A represents the plow-beam, which is constructed of wrought-iron and of bent or curved form, the back end extending downward and terminating in a loop, a, through which the foot B of the plow passes, the back end of the beam being secured to the foot by a bolt, b, which passes through either of a series of holes, c, in the foot. The beam is quite flat—that is to say, of much greater depth than width—and it gradually tapers from its curve d toward either end, as shown clearly in the figures. The foot B is also constructed of a flat metal bar, increased in thickness at its lower end so as to form a good bearing for the share C, which is secured to the foot by a bolt, e, the upper edge of the share being notched to receive a shoulder, f, of the foot, in order to prevent the turning of the share on the bolt.

D D are two flat metal bars, the front parts of which are secured by bolts g to the curve of the beam A. The back parts of these bars are secured by a bolt, h, to the upper part of the foot B, said bolt h passing through either of a series of holes, i, in the foot.

To the upper part of the foot B the handles

E E are attached. These handles are constructed of flat metal bars the lower parts of which are slotted longitudinally, as shown at j, to allow the bolt h to pass through. The lower parts of the handles are secured to the foot by bolts k k, which pass through holes of the series i. The handles are connected by a traverse-rod, l.

From the above description it will be seen that the beam A may be raised and lowered on the foot B by simply removing the bolts b h and inserting them in different holes of their respective series, c i, thereby lengthening or shortening the foot B.

It will also be seen that the handles E E may be raised and lowered on the foot B by removing the bolts K K and adjusting them in the proper holes i, and that the point of the beam may be elevated as required by adjusting the back ends of the bars D D higher or lower in the series of holes i, the slot j in the lower parts of the handles E E admitting of the facile adjustment of the bars D D. This adjustment of the bars D varies the position of the share C relatively with the earth. In the front end of the beam A a flat plate, l, is secured, said plate being perforated in order that a single-tree may be attached to it.

The adjustment of the several parts of the plow as described does not render it at all complex or expensive to construct, and at the same time adds greatly to its value, as it may be adapted to the team, the attendant, and to the character of the work to be performed.

I do not claim constructing the several parts of metal; but

I do claim as new and desire to secure by Letters Patent—

The arrangement of the beam A, bars D D, foot B, and handles E E, as shown and described, in order to admit of the adjustment of the parts, as and for the purpose set forth.

SAMUEL WALKER.
